US00D911192S

(12) **United States Design Patent** (10) Patent No.: **US D911,192 S**
(45) Date of Patent: **** Feb. 23, 2021**

(54) **GOLDEN RATIO DIVIDER**

(71) Applicant: **PHIACADEMY DOO BEOGRAD,**
Belgrade (RS)

(72) Inventor: **Branko Babic**, Belgrade (RS)

(**) Term: **15 Years**

(21) Appl. No.: **35/507,865**

(22) Filed: **Jul. 31, 2019**

(80) **Hague Agreement Data**

Int. Filing Date: **Jul. 31, 2019**

Int. Reg. No.: **DM/204106**

Int. Reg. Date: **Jul. 31, 2019**

Int. Reg. Pub. Date: **Nov. 22, 2019**

(30) **Foreign Application Priority Data**

Jul. 11, 2019 (RS) D-2019/0067

(51) LOC (13) Cl. **10-04**

(52) U.S. Cl.

USPC **D10/65**

(58) **Field of Classification Search**

USPC D10/71, 65

CPC G01C 21/20

See application file for complete search history.
